UNITED STATES PATENT OFFICE.

ALBERT A. SILVERMAN AND DANIEL SILVERMAN, OF ASHEVILLE, NORTH CAROLINA.

RADIO QUESTIONER AMUSEMENT APPARATUS.

Application filed April 4, 1925. Serial No. 20,774.

To all whom it may concern:

Be it known that we, ALBERT A. SILVERMAN and DANIEL SILVERMAN, citizens of the United States, residing at Asheville, in the county of Buncombe and State of North Carolina, have invented new and useful Improvements in Radio Questioner Amusement Apparatus, of which the following is a specification.

10 This invention relates to amusement apparatus, particularly to question and answer devices, and has for its object the provision of a novel apparatus constructed to resemble a radio receiving set and so arranged 15 that various questions may be asked and the answers thereto accurately obtained.

An important and more specific object is the provision of an apparatus of this character, constructed in cabinet form and provided with a panel upon which are mounted dials resembling the dials employed in radio receiving sets, one dial being so arranged as to be rotatable and to point to a selected question and the other dial being correspondingly rotatable in order to ascertain the answer, the obtaining of the correct answer being indicated by illumination of a lamp within the device and the operation of a buzzer.

Another object is the provision of a device of this character which is electrically controlled or operated, the questioning and answering dials forming part of switches, the respective contacts of which are connected so that the two switches will act in effect in the same manner as the combination on a commutation lock, it being absolutely necessary that both switches be in corresponding positions in order that the correct answer to a certain question will 40 be had.

Yet another object is the provision of a device of this character in which the current utilized may be taken from an ordinary flashlight cell easily removably mounted in place so as to be capable of replacement when such is necessary for any reason.

An additional object is the provision of a device of this character which will be simple and inexpensive in manufacture, easy 50 to operate, instructive as well as amusing, positive in action, efficient and durable in service, and a general improvement in the art.

With the above and other objects and advantages in view, the invention consists in the details of construction to be hereinafter

more fully described and claimed, and illustrated in the accompanying drawings in which:

Figure 1 is a vertical section looking at 60 the back of the front panel and showing the entire electrical system,

Figure 2 is a vertical section taken substantially along the center of Figure 1,

Figure 3 is a perspective view of the complete device,

Figure 4 is an elevation of one of the question bearing disks,

Figure 5 is an elevation of one of the answer bearing disks,

Figures 6 and 7 are similar views of other disks, and

Figure 8 is detail view illustrating a modification.

Referring more particularly to the drawings I have shown the device as enclosed within a suitable cabinet 10 provided at its front with a panel 11 and so constructed and arranged as to resemble a radio receiving set. Rotatably mounted on the panel 75 are dials 12 and 13 having pointers 12^a and 13^a thereon having operating knobs 14 and constructed in exactly the same manner as the dials and knobs used in radio sets, the dials being here shown as carrying shanks 85 15 journaled through bearings 16 in the rear side of the panel and equipped with springs 17 acting to hold the dials snugly to the panel for preventing wabbling while in use. Above the dial 12 the panel is inscribed with 90 the legend "Questions" and above the dial 13 with the legend "Answers". The panel is provided with a series of openings 18 between these two legends for a purpose to be described. The lower portion of the 95 panel may be utilized for the inscription of advertising matter and the like and the representation of other parts of a radio apparatus may be applied if such is desired. While it is not essential the openings 18 100 above referred to may be bushed or provided with internal ferrules 19 as shown in order to improve the appearance.

The dial shanks carry switch arms 20 and 21 respectively movable over two series of contacts 22 and 23 respectively, the corresponding contacts being connected by conductors 24 in a manner well illustrated in Figure 1. It is immaterial which of the contacts 22 are connected with the contacts 23 except that they should run in sequence. In the present instance the topmost contact 105 110

22 is shown as connected with the lowermost contact 23 but this is an arbitrary arrangement. Mounted on the bottom of the cabinet is a suitable supporting bracket 25 which is of metal and which constitutes a common ground for the various elements of the mechanism, and mounted upon this bracket are upstanding contacts 26 and 27, the former of which is in electrical connection therewith and the other of which is insulated therefrom, and also mounted on the bracket is a spring clip 28 adapted to receive and hold a dry cell 29 of the type used in flashlights. A contact screw 30 is carried by the contact 26 and is adapted to engage the central terminal 31 of the cell. Threaded through the contact member 27 is a screw 32 designed to bear clampingly against the adjacent end of the cell.

20 Mounted within the cabinet back of the openings 18 therein is a reflector 33 formed with a socket portion 34 within which is screwed or otherwise held an incandescent lamp 35 of the single contact type having its shell grounded on the reflector and having its contact 36 engaging a contact 37 secured upon and insulated from the reflector. The contact 37 has connected therewith a conductor 38 connected with the contact 27, and connected with the reflector 33 is a conductor 39 connected with the bracket 16 associated with the dial 12. Connected with the bracket 16 associated with the dial 13 is a conductor 40 connected with the contact 26.

35 While it is not absolutely necessary, we prefer to provide a buzzer 41 of conventional construction mounted at some convenient location, preferably on the bracket 25 and having one of its terminals connected with this bracket by a conductor 42. This buzzer includes the usual vibrator structure 43 with which is connected a conductor 44 connected with the conductor 39.

45 In conjunction with the dials we provide disks 45 and 46 both of which have open central portions so as to encircle the dials 12 and 13 respectively when placed on the front of the panel. It is intended that these disks bear questions and the corresponding answers as clearly indicated in Figures 4 and 5 and also in Figures 6 and 7, the questions and answers being of any character desired but not really intended to be absurd inasmuch as one of the primary purposes of the

50 invention is to provide an instruction device. For this reason the questions and answers are represented as being historical though there is no limitation in this respect. The disks are shown as provided at their upper and lower edges with apertured edges 47 and 48 respectively adapted to be engaged upon hooks 49 and pins 50 projecting from the front of the panel above and below the dials 12 and 13. By this arrangement it is evident that the disks 45 and 46 may be re-

moved and replaced by similar disks 45^a and 46^a which bear a different series of questions and answers. It is a convenience that both sides of each disk have questions or answers thereon in order to increase the range of changes which may be made.

In the modification shown in Figure 8 the buzzer above described is replaced by a ratchet device including a ratchet wheel 51 carried by the shank of the dial 13 and engaged by a spring pawl 52 so as to produce a clicking noise when the dial 13 is turned.

In the operation, the dial 12 is turned to bring the pointer 12^a thereon into such position that it will point to any desired one of the questions on the disk 45. Obviously, when this is done, the switch arm 20 will be in engagement with one of the conductors 24. The operator then grasps the knob of the other dial 13 and turns it. When the switch arm 21 controlled by the dial 13 is in such position that the pointer 13^a thereon points to the proper answer on the disk 46 this switch arm 21 will be in engagement with the contact 23 connected with the contact 22 engaged by the switch arm 20. This obviously completes the circuit through the incandescent lamp 35 and also through the buzzer 41 so that a light will be displayed through the openings 18 and a sound will be given off by the buzzer. When this occurs it will indicate that this is the correct answer to the question asked.

In the modification disclosed in Figure 8 wherein the buzzer is omitted, it is obvious that whenever the dial 13 is turned the ratchet 51 coacting with the pawl 52 will act to give a buzzing sound. However, in this form, this sound does not mean that the correct answer has been reached, this indication being given by the illumination of the incandescent lamp 35.

It will be observed that the disks 45 and 46 may be turned over so that the other sides thereof may be used and it is also quite clear that these disks may be removed and replaced by others such as those indicated in Figures 6 and 7 in order to provide a wide range of questions and answers. The peculiar manner of mounting these disks on the front of the panel is of particular advantage inasmuch as it permits ready removal and replacement without disturbing any of the apparatus.

From the foregoing and a study of the drawings it will be apparent that we have thus provided a simply constructed, inexpensive and very amusing device which will have the great advantage of being instructive in its nature as well as entertaining. Owing to the simplicity of the construction it is apparent that there is very little to get out of order so that the device should have a long and satisfactory life.

While we have shown and described the

preferred embodiment of the invention, it should be understood that we reserve the right to make such changes in the form, construction and arrangement of parts as will not depart from the spirit of the invention or the scope of the subjoined claims.

Having thus described the invention, we claim:

1. In an apparatus of the character described, a plurality of interrupted circuits all connected with a common source of current and with a common indicator, means for closing a selected circuit at one of the interruptions therein, means indicating which circuit has had an interruption therein bridged, means for closing or bridging the other interruption in the selected circuit, and indicating means at last named means.
  2. In a device of the character described, a cabinet, a panel mounted thereon, a pair of dials rotatably mounted on the panel and carrying pointers, a pair of disks on the panel arranged in surrounding relation to the dials, one disk carrying a series of questions and the other bearing a corresponding series of answers, an electric play responsive indicator within the cabinet, a source of current within the cabinet, and a pair of switches operated by movement of the dials and including movable arms and a series of contacts corresponding to the questions and answers respectively and connected in circuit with the source of current and the indicator.
  3. In a device of the character described, a cabinet, a panel mounted thereon, a pair of dials rotatably mounted on the panel and carrying pointers, a pair of disks on the panel arranged in surrounding relation to the dials, one disk bearing a series of questions and the other bearing a corresponding series of answers, an electric play responsive indicator within the cabinet, a source of current within the cabinet, and a pair of switches operated by movement of the dials and including a movable arm and a series of contacts corresponding to the questions and
- answers, respectively, and connected in circuit with the source of current and the indicator, the disks being removably mounted and having both sides similarly formed whereby to be capable of reversal.
4. In a device of the character described, a cabinet, a panel mounted thereon, a pair of dials rotatably mounted on the panel and carrying pointers, a pair of disks on the panel arranged in surrounding relation to the dials, one disk bearing a series of questions and the other bearing a corresponding series of answers, an electric play responsive indicator within the cabinet, a source of current within the cabinet, and a pair of switches operated by movement of the dials and including a movable arm and a series of contacts corresponding to the questions and answers, respectively, and connected in circuit with the source of current and the indicator, and means for detachably mounting the disks in place whereby selective disks may be employed.
5. In a device of the character described, a cabinet, a panel mounted thereon, a pair of dials rotatably mounted on the panel and carrying pointers, a pair of disks on the panel arranged in surrounding relation to the dials, one disk bearing a series of questions and the other bearing a corresponding series of answers, an electric play responsive indicator within the cabinet, a source of current within the cabinet, and a pair of switches operated by movement of the dials, and including a movable arm and a series of contacts corresponding to the questions and answers, respectively, and connected in circuit with the source of current and the indicator, the disks being provided with apertured lugs, and retaining elements projecting from the panel and upon which the apertured lugs are engaged.

In testimony whereof we affix our signatures.

ALBERT A. SILVERMAN.
DANIEL SILVERMAN.
